Filed Feb. 1, 1962, Ser. No. 68,605

Term of patent 14 years

(Cl. D9—6)

FIG. 1

FIG. 1 is a top plan view of a combined stove top mat and cutting board holder embodying my new design.

FIG. 2 is a fragmentary enlargement of the upper right hand corner of FIG. 1.

FIG. 3 is an enlarged side elevation thereof, a cutting board being shown in broken lines for illustrative purposes only.

FIG. 4 is a longitudinal sectional view thereof.

FIG. 5 is a fragmentary elevational view of the right side thereof;

FIG. 6 is a fragmentary elevational view of the right side thereof.

FIG. 7 is an enlarged fragmentary section thereof taken along line 7-7 of FIG. 1.

FIG. 8 is a still further enlarged fragmentary section thereof taken along line 8-8 of FIG. 1.

FIG. 9 is also a further enlarged fragmentary section thereof taken along line 9-9 of FIG. 1.

A portion of the mat is broken away in FIGS. 3 and 4 for convenience of illustration.

The bottom of the mat is substantially flat and plain. I claim:

The ornamental design for a combined stove top mat and cutting board holder, substantially as shown and described.
